CLAIM

The ornamental design for a wind power generator, as shown and described.

DESCRIPTION

FIG. 1 is a perspective view of a wind power generator showing our new design;

FIG. 2 is a top plan view thereof;

FIG. 3 is a front elevational view thereof;

FIG. 4 is a bottom plan view thereof;

FIG. 5 is a back elevational view thereof;

FIG. 6 is a right side elevational view thereof; and,

FIG. 7 is a left side elevational view thereof.

Broken lines are used in the drawings to illustrate features of the wind power generator that form no part of the claimed design.
